UNITED STATES PATENT OFFICE.

JOHN C. TYMS, OF GARFIELD, NEW JERSEY.

DESIGN FOR A TEA-KETTLE.

SPECIFICATION forming part of Design No. 35,379, dated December 3, 1901.

Application filed October 3, 1901. Serial No. 77,604. Term of patent 7 years.

To all whom it may concern:

Be it known that I, JOHN C. TYMS, a citizen of the United States, residing at the corner of Cambridge and Grant streets, Garfield, county 5 of Bergen, State of New Jersey, have invented and produced a certain new and useful Design for a Tea-Kettle, fully described and represented in the following specification and the accompanying drawings, forming a part of the same.

In the annexed drawings, Figure 1 is a vertical section of a tea-kettle embodying my design, and Fig. 2 represents the under side of such kettle.

5 The body *a* of the kettle, with its spout *b* and lid-opening *c*, is of the form usually employed for cast-iron kettles.

The lower portion of the kettle is formed in the present design with a circular tapering chamber *d* of less diameter than the body *a*, forming a flat annular shoulder *g*. A dome *e* projects upwardly in the bottom of the cham-

ber at the center, with upwardly-inclined passages *f* leading from the sides of the dome to the outer sides of the shell *d* around the chamber. The passages are considerably less in width than the downward extension of the chamber *d*, so that the passages have a considerable upward inclination from the bottom of the dome to the sides of the shell *d* beneath 25 the shoulder *g*.

Having described my invention, what I claim as new, and desire to secure by Letters Patent, is—

The design for a tea-kettle as herein shown 35 and described.

In testimony whereof I have hereunto set my hand in the presence of two subscribing witnesses.

JOHN C. TYMS.

Witnesses:

THOMAS S. CRANE,
L. LEE.
